POURING REGULATING SPOUT FOR
BOTTLES

Edward Sokolik, New Brighton, Minn.

Application September 12, 1949, Serial No. 115,140

3 Claims. (Cl. 222—566)

1

This invention relates to pouring regulating spouts for bottles, and particularly to a spout, in which the volume of liquid flow can be precisely regulated by easy manipulation in the ordinary operation of pouring, and still be instantly subject to full capacity flow.

Bottle stoppers and pourers have been devised, but there is still lacking a pouring spout, which permits of full capacity flow although precise regulation of flow is instantly obtainable, by easy manipulation in the ordinary operation of pouring. Stopper caps, with small tubes inserted through same, have been used. These provide refinement in the volume of liquid flow, according to the smallness of the tube, but do not permit of any larger volume of flow. It is evident that use of same is too time consuming, and does not meet the needs in dispensing liquors or preparing medicines and chemicals. One type of spout has been devised for dispensing a certain quantity of chemical, like nitrate of silver for photographic work. This consists of a tube with a chamber enlargement at its extremity, including a lid and with an upward bend in the tube leading to the chamber. The chamber is filled by tipping up the bottle, and then by holding the bottle in horizontal position, the liquid flows back into the bottle, except that which is in the chamber. By opening the lid, this measured amount is released. This device is limited to a particular use, as it must be specially formed to dispense the certain amount desired. Improvements have been made in stopper caps, lids, vents and sealing valves but not in a flow regulating device; permitting instant change from maximum to minimum, without refinement in manipulation. To dispense from any ordinary bottle in proper amount is difficult, requiring extremely skillful and slow handling in tilting and angling the bottle.

An important object of my invention is to provide a pouring regulating spout for bottles, in which the volume of liquid flow can be precisely regulated by easy manipulation in the ordinary operation of pouring, and still be instantly subject to full capacity flow.

Another important object is to provide such a pouring regulating spout, which can be readily applied to and removed from a bottle, and which has a closure which seats itself when the bottle is in upright position, protecting the contents of the bottle from contact with the atmosphere.

Another object is to provide such a pouring regulating spout, which can be easily cleaned and maintained in a highly sanitary condition at all times.

Another object is to provide such a pouring regulating spout at a reasonable cost.

Other objects will be apparent from the description and appended claims.

For a full disclosure of my invention, refer-

ence is made to the description following, and to the drawings, in which:

Fig. 1 is a side elevation view of my pouring regulating spout, as it would appear if placed on a bottle in an upright position, but having a portion broken away to show a sectional view of the lower portion thereof.

Fig. 2 is an elevation view, as viewed from the right side of Fig. 1, but with a portion broken away to show a sectional view of the middle portion thereof.

In my improved pouring regulating spout, which is hereby disclosed, I provide it preferably, in two sections 3 and 4, constituting respectively the top and bottom portions. These portions are medially joined by a slip joint 5. This joint may be of stepped construction, as shown by the drawings, providing smooth flush interior and exterior surfaces, or may be a plain overlapping telescoping joint. In either case, the two portions can be easily separated for washing and cleaning of the interior, and then fitted together again. The joint 5 might be dispensed with and the two portions 3 and 4 molded so as to be permanently integral, and the spout still not be too difficult to clean. The end 6 of the section 3, is for general use, shaped to provide a round orifice from which to pour. A hinged lid 7 is mounted at the end 6 to normally keep the orifice closed, but to swing open for pouring and obviates the necessity of removing and replacing a stopper at frequent intervals for dispensing. This is accomplished because the end 6 is on the bias, and also the section 3 has an arcuate portion 8 definitely maintaining the lid 7 in such position by gravity. When pouring, the lid 7 may also be tipped back into reverse position against the spout. The arcuate portion 8, in addition to the purpose above stated, also facilitates in pouring, as the shape directs the liquid downward. The section 4 is provided with a round tubular shank 9, which extends through a stopper cap 10 and gives access to the contents of the bottle. The opening 13 in this tubular shank is of substantial diameter, to permit fast pouring, and normally would be of the same diameter as the orifice at the end 6. The stopper cap 10 is of quite conventional construction, and consists of a cap with a downward extending brim over the neck 50 of the bottle and with a stopper of cork or similar material to closely fit within the opening in the bottle, and the cap and stopper perforated to closely fit over the tubular shank 9. In the middle of the device, I provide a passageway 14 of 55 restricted width but of such height, that its cross sectional area is equal to the cross sectional area of the orifice in the end 6 or of the opening 13. The device would still be operable even though the passageway were larger or smaller than the 60 openings 6 and 13, and even though these openings were not equal in area, but for smooth flow

without turbulence, the cross sectional area of all should be the same. With this passageway necessarily flushing with the bottom pouring line of the spout, it requires a construction with an extension 11 upward from the pouring line. The passageway is substantially rectangular except for rounded corners, and the transition, between it and the round tubular sections at the respective extremities of the spout, is accomplished by a construction tapering inwardly to the sides of the passageway and with sloping portions 12 inclined upwardly to the top of the passageway. The entire spout construction is of course in symmetry about a median plane on the long axis of the passageway. It is not necessary to provide any vent in the device, as the quantities dispensed are usually small, not requiring ingress of outside air. The construction itself is also conducive to entrance of air into the bottle, resulting in a smooth flow. The device can be made of any suitable material, but is preferably made of plastic, except for a cork stopper and a metal hinge pin. For clear liquids, transparent material would be preferable, but for colored liquids certain color combinations would be attractive. The broad relatively flat surface on each side of the device, provides ample space for embossing or otherwise affixing a monogram, emblem or mark of a manufacturer, and also for attaching a label to denote contents of bottles.

From the foregoing it is apparent how my pouring regulating spout is constructed and that it must have many desirable features. It provides for a smooth flow of liquid, and increases the refinement in regulation of flow, without requiring any special skill in the handling of the bottle. By converging the flow from the round opening from the bottle into a narrow but high passage way, the flow gaging factor of the device is greatly increased. This, therefore, requires corresponding decrease in skill of the dispenser. He can dispense accurately without much effort and can do it very quickly. Since the area of the narrow but high passage way is equal to the round opening from the bottle, a full capacity flow is available, which can be instantly reduced by tipping down the body of the bottle, and then by the great latitude of gaging provided by the passage way, be easily manipulated to the refinement required. In a conventional round spout, the flow of liquid is increased or reduced very abruptly by a corresponding tipping of the bottle, so even a very skilful dispenser will pour too much or not enough, unless he takes considerable time. In the case of a pharmacist, whose measuring of quantities is usually very precise, the pouring of liquids is a painstaking and time consuming work. By the use of my device, a full flow is represented by the relatively great height of the passage way. Any flow, lesser than a full flow, is clearly apparent from the level of the liquid in the passage way. Since the passage way is of rectangular cross section, the amount of flow is in direct proportion to the height of the level of the liquid. This, as contrasted with a round orifice, is easy to gage, and since the flow is restricted to a narrow width, it is obvious that the flow, if desired, can be quickly reduced to a very small amount, so it can be closely but easily regulated.

While I have drawn and described a preferred form of my invention, it is obvious that many changes, which are within the scope of my invention, will be apparent to those skilled in the

art. I therefore desire to be limited only by the scope of the appended claims.

What I claim is:

1. A pouring regulating spout for bottles, comprising an upper discharge section and a lower bottle engaging section, said sections being medially joined by a slip joint and each section having a transition from substantially round and equally sized openings at their respective extremities to a substantially rectangular equal area conduit of narrow width at said juncture, said upper section having a hinged lid over the opening at its extremity positioned to keep said opening closed when the bottle is in its normal upright position, said lower section having a stopper cap with a perforation engaged by the lower extremity of said section and adapted to engage and position said spout on a bottle, said rectangular conduit rising from the pouring line of said spout, whereby the flow through the round opening from the bottle is converged into a narrow but high passage way, so that the flow gaging factor is greatly increased, requiring less skill on the part of the dispenser to quickly and easily regulate the flow.
2. A device of the class described, comprising a lower portion with a tubular shank engageable in a bottle, an upper portion with a discharge orifice at its upper extremity and in slip joint engagement with said lower portion, said slip joint being of stepped construction with flushing surfaces, said portions at said engagement being of substantially rectangular cross section of a narrow width and in symmetry about the long axis of the rectangular cross section, said portions having transitions respectively from substantially round and equally sized openings in said shank and said orifice to said substantially rectangular cross section also of equal area to each of said openings, said transitions having an unbroken pouring line on one side and abrupt angular outward extensions on the other side forming a narrow passage way of substantial height, whereby precise regulation of flow is attainable by easy manipulation in the ordinary operation of pouring and still the pouring be instantly subject to full capacity flow, said lower portion having a stopper cap fitting over the shank thereof and making tight engagement with a bottle, said upper portion having a hinged lid over its discharge orifice positioned to permit pouring but to keep said orifice closed when the bottle is in an upright position, and said upper portion having an arcuate bend to facilitate positioning of said lid and to direct flow from said orifice downward.
3. A pouring regulating spout for bottles, comprising a unitary body portion; a hinged gravity closing lid over the top thereof, a stopper cap for engaging a bottle attached to the bottom thereof, a channel in said body provided with substantially round and equally sized openings at each end and with a transition to a substantially rectangular equal area cross section intermediate thereof, said body having an unbroken pouring line on one side and an abrupt angular outward extension on the side opposed thereto forming said rectangular cross section, said cross section having a narrow width relative to its height, whereby the flow gaging factor is greatly increased by convergence from a round opening into a narrow but high passage way, requiring less skill on the part of the dispenser to quickly and easily regulate the flow.
